CLAIM

The ornamental design for the roll-off portion of a bucket, as shown and described.

DESCRIPTION

FIG. 1 is a perspective view of a roll-off portion of a bucket for paint trays, buckets and containers showing our new design; FIG. 2 is an elevation view of the roll-off portion of a bucket for paint trays, buckets and containers; and, FIG. 3 is another perspective view of the roll-off portion of a bucket for paint trays, buckets and containers.

The broken lines depicting a paint container shown in the figures are for illustrative purposes only and form no part of the claimed design.
